(57) **CLAIM**

The ornamental design for a drilling tool, as shown and described.

DESCRIPTION

4. Drilling tool

4.1: Perspective

4.2: Front

4.3: Back

4.4: Right

4.5: Left

4.6: Top

4.7: Bottom

4.8: Enlarged

4.9: Partial enlarged view of broken line rectangle in fig. 4.2
With the exception of the broken line rectangle in figure 4.2
which illustrates a partial enlarged view, the broken lines in
the reproduction illustrate portions of the drill bit that form
no part of the claimed designs; the dot-chain lines illustrate
a border of the claimed subject matter and form no part of
the claimed design.
